UNITED STATES PATENT OFFICE.

ALBERT M. POWELL, OF SHREWSBURY, MASSACHUSETTS.

CUT-SPEED-ACCELERATING DEVICE.

Application filed August 6, 1921. Serial No. 490,231.

To all whom it may concern:

Be it known that I, ALBERT M. POWELL, a citizen of the United States, residing at Shrewsbury, in the county of Worcester 5 and State of Massachusetts, have invented a new and useful Cut-Speed-Accelerating Device, of which the following is a specification.

While capable of general use, this invention is particularly adapted for driving a planer, engine-lathe, or other machine tool for the purpose of increasing the speed of the work or the cutting tool, after the tool enters the work in its forward cutting direction.

The principal objects of the invention are to provide an improved device whereby the in-cut speed of a planing machine or the like may be increased and retarded at will after the tool has entered the work at its low speed, and while in cutting action, without stopping or shifting out the low cutting speed means; to provide an arrangement which will constitute an improvement over my prior Patents Nos. 934,837 and 1,013,439, in which the slow and accelerating speed action was secured by means shown as connected to and constituting a part of the main or driving shaft of the planer itself; to provide this improvement in a form in which the rotating element that carries the speed-changing mechanism can itself be arranged to rotate constantly in the same direction and preferably at the same speed instead of applying this mechanism to the planer driving shaft which must itself be rotated in a forward and reverse direction alternately and at varying speeds. The improvement, therefore, relates to that part of the planer comprising a countershaft, or some equivalent thereof, which constantly rotates in one direction. This countershaft may be attached to and be a part of the planer structure, or it may be separate and bolted to the ceiling or other part of the shop. It may receive its power by belt from a main line shaft or may have a motor connected directly to it for driving it. Further objects and advantages of the invention will appear below.

Reference is to be had to the accompanying drawings, in which

Fig. 1 is an end elevation of a planer shown with the invention applied thereto in a simple form;

Fig. 2 is a side elevation of the same; Fig. 3 is a side elevation of the slow speed

driving pulley on the countershaft with its connecting elements illustrated on enlarged scale;

Fig. 4 is a diagrammatic view showing a modified way of driving the planer shaft or the like from a countershaft in accordance with this invention;

Fig. 5 is a similar view showing another modification;

Fig. 6 is a side view, partly in section, of the driving device for the slow speed part of the transmission, and

Fig. 7 is a view similar to Fig. 4 of another form of the invention.

Referring first to the first sheet of drawings, it is to be noted that I have shown the invention as applied to a well-known type of planer having a bed or frame 10 and a reciprocating table 11 for carrying the work under a tool-carriage 12 of well known form. This planer is shown as having the usual driving shaft 13 adapted to be driven by a countershaft 14. This countershaft may be hung down from the ceiling if desired, but I have shown it mounted on brackets 15 carried at the top of the frame 16 which supports the tool carriage of the planer.

The countershaft 14 is driven by belts on tight and loose pulleys 17, or by motor if desired, constantly in one direction and preferably at a constant speed. I have indicated several pulleys on the countershaft and the driving shaft, and by the letters T and L indicated which are the tight pulleys and which are the loose pulleys. In the first place there are three wide-faced pulleys 20, 21 and 22 on the countershaft 14. The pulleys 20 and 21 are tight pulleys in the ordinary sense, as they are keyed directly to the shaft. The pulley 22 is called a tight pulley because it is positively driven by the shaft, although it is not keyed directly to it as will appear. The pulley 20 is shown as driving, by a cross belt, a pair of pulleys 23, one tight and one loose on the shaft 13. A pair of tight and loose pulleys 24 are driven by the pulley 21, and a pair of tight and loose pulleys 25 by the pulley 22. The belts on the pulleys 20 and 22 are both of the same character, that is, if one is a cross belt, both are, while the belt on the pulley 21 is of the opposite character, in this case an open belt.

One purpose of these several pulleys is to drive the driving shaft 13 and therefore the table 11 through any usual connection at a low speed forward for the cutting stroke

through the pulleys 22 and 25 to introduce the tool into the work at a comparatively low speed. The pulley 20, through the tight pulley 23, drives the shaft 13 at a high speed 5 in the same direction. That is, it is intended to take up the driving of the shaft 13 and accelerate it after the tool enters the work. The pulleys 21 and 24 are for driving the shaft 13, and consequently the table 12, in 10 the reverse direction for the reverse or non-cutting stroke.

Fixed on the countershaft 14, that is keyed to it, is a drum 26. This drum carries a ratchet pawl 27 constantly pressed by a 15 spring 28 against an internal circular ratchet 29 which constitutes a part of the pulley 22, in the form shown, the inside of its hub. The ratchet pawl extends forwardly in the direction of rotation of the countershaft 14, 20 and the teeth of the ratchet extend in the same direction. Therefore, under normal conditions, the shaft 14, through the pawl 27, constantly drives the pulley 22 forwardly at the angular velocity of the countershaft. 25 This pulley, being smaller than the pulley 20 and the pulley 25 being preferably larger than the pulley 23, power is thus transmitted to the driving shaft 13 at a slow speed.

Now, however, if it is desired to increase 30 the speed of the table, after having introduced the tool into the work at slow speed as just above indicated, the belt on the pulley 20 can be shifted over to the tight pulley from the loose pulley. On account of the 35 relationship of the pulleys 20, 22, 23 and 25 the shaft 13 will now be rotated at a higher speed for the remainder of the cutting stroke until the belt on the pulley 20 is shifted back to the loose pulley. The effect 40 of this is to drive the pulley 22 by means of the pulley 25 in a forward direction, but at a higher speed than it would be driven by the countershaft 14 through the ratchet mechanism shown in Fig. 3. This acceleration 45 can take place in any degree, and with any desired rapidity of change. Because of the ratchet arrangement, the pulley 22 simply rotates faster than the drum 26 and the pawl ratchets over the ratchet teeth in 50 what is relatively a backward direction, although both are moving forward.

In the description above given it will be obvious that the changes can be made by hand belt shifters if desired, and that the 55 two belts on the pulleys 20 and 22 can be shifted to the loose pulleys as shown in Fig. 1, and the belt on the pulley 21 shifted by hand to its tight pulley to reverse the table at a high speed. However, I have shown, 60 especially in Fig. 2, means for accomplishing this automatically as follows:—

A dog 30, adjustable along the planer table, operating on a rocker 31, shifts the return belt on its loose pulley 24 and the 65 momentum of the table further advances

the rocker 31, shifts the low cut speed belt from its loose pulley 25 on its tight pulley, which reverses the direction of table movement towards and against the cutting tool. The table continues to move in this direction, at this low speed, until dog 32, which is adjustable on the table, strikes lever 33, which is connected to the belt shifting mechanism, and moves the high speed cut belt from its loose pulley 23 on its tight pulley. 70 This turns the shaft in the same direction at a higher speed than the first or low speed cut belt, the increased speed increases the velocity of travel of low speed cut belt and, by means of the ratchet pulley on the counter shaft, releases itself and remains loose until dog 34, also adjustable on table, advances and engages or strikes rocker 35. This depresses the latter, moving the belt shifting mechanism backwards, which moves the high speed cut belt off its tight pulley 23 on its loose pulley. Then the low speed cut belt again takes hold and advances the table at the low cut speed, until dog 36, adjustable on the table, engages or strikes rocker 37. This further depresses the latter, moves the belt shifter mechanism backward, throwing off the low cut speed belt from its tight pulley 25 on its loose pulley, 80 and further moving the high speed return belt on its tight pulley 24. Then the driving shaft turns in the opposite direction, and the table moves on its backward return or non-cutting stroke. This return or backward travel continues until dog 30 again 85 engages rocker 31 when the high speed return belt is thrown off its tight pulley 24 on its loose pulley and the low speed cut belt is again moved from its loose pulley 23 on its tight pulley. Then the table again 90 moves forward on its cutting stroke as before. A conventional form of belt shifter is indicated in the drawings.

The addition of other accelerating and retarding dogs adjustable on the table, in 95 an obvious way, would allow the acceleration and retardation of the forward cutting stroke of the table as often as may be desired to meet the requirements of the work to be planed, in other words, work consisting of spots to be planed and open spaces not to be planed. The cutting tool can plane the spots at low speed and jump over gaps or spaces at high speed thereby saving very materially the usual time of planing with the regular one speed cutting planer. I do not wish to confine myself to the use of my invention in the planing machine alone, but its application to other machines or mechanism where it is desirable and profitable 100 to increase its work, producing speeds from a low speed to a high speed during action without stopping the continuity of action when a low speed is changed to a higher speed and reverse.

In this way it will be seen that I have avoided the location of the means for acceleration on the main driving shaft of the planer structure itself and thus simplified the arrangement, because I have placed it on a shaft which rotates constantly in a single direction and preferably at a constant speed. This not only simplifies the construction, and reduces repairs, but it reduces the amount of static energy wasted in the reversing of the parts each time the planer table is reversed or accelerated. In this way a serious handicap present in former constructions is avoided. I wish it to be distinctly understood that I am not claiming any novelty in this patent over the form of dogs and belt shifting control set forth in my prior patents. If the machine should be speeded up too high for the work at hand, so that the high cut speed belt would be thrown off, the low speed device would come into operation automatically.

In the form of the invention shown in Fig. 4, substantially the same conditions are present, except that the tight pulley 20 has substituted for it a tight cone pulley 40 and a corresponding cone pulley 43 on the driving shaft for producing a number of degrees of acceleration. The cone pulley 43 is itself loose on the driving shaft and is connected with it by a clutch 44 operated by a shifting rod 45 to clutch it to the shaft as desired. This constitutes the only change in this form, and no further explanation is necessary. I have shown the driving shaft as provided with a pinion 46 driving a gear 47 which, through pinion 48, drives a gear 49 which directly operates the table.

In the form shown in Fig. 5 the conditions prevailing in Fig. 1 are repeated, except that the forward reverse driving pulleys 20 and 21 are combined so as to have only one tight pulley between the two loose pulleys of the driven pair shown below in that figure. In this case the corresponding pulleys below are also combined and I have shown another modification in that the pulleys 25 are not mounted on the driving shaft 13, but on a separate shaft 50 which in turn, through gears 51, drives the shaft 13 when connected for that purpose. In this case the ratchet mechanism illustrated in Fig. 6 is mounted on the main driving shaft 13 in connection with the gears 51. It operates just the same as in Fig. 1, and need not be described further in detail. In this form some of the advantages set forth in connection with Fig. 1 are not secured because the ratchet mechanism is on a shaft which is reversed.

In the form shown in Fig. 7, conditions are very nearly the same as those shown in Fig. 4, as I have merely substituted a geometrical cone pulley 60 for the conventional

cone pulley 30, and of course the same is true of the driven cone 63.

However, another modification is shown herein as the shaft 13 is not driven either forward or back directly by the pulleys on the countershaft, but is driven through an intermediate shaft 64 on which the pulley 63 is mounted. The reversing pulley 21 drives tight and loose pulleys 24 located on this shaft 64 also which drives the shaft 13 through gears 61. In this case the pulley 60 has two cylindrical portions, one for the incut at the small end of the cone and the other for the acceleration at the large end of the cone, and a belt shifting arrangement 65 is provided capable of shifting the belt all the way up the cone. In this case also the ratchet mechanism is located in the gear 61 as in Fig. 6.

Although I have illustrated and described several forms of the invention I am aware of the fact that other modifications can be made therein and that the invention can be applied to other machines than planers or even machine tools in general without departing from the scope of the invention as expressed in the claims.

Therefore I do not wish to be limited in these respects, but what I do claim is:

1. In a machine having a working part movable back and forth, the combination of a shaft arranged and adapted to be driven constantly in the same direction, and a shaft on said machine connected with said working part to operate it, of power and speed transmission means fast on the first named shaft and connected with the second shaft to operate the second shaft from the first shaft in one direction at a slow speed and in the opposite direction at a rapid speed, and means mounted on the first shaft and connected with the second shaft to transmit power to the second shaft in the direction in which it is driven by said slow speed means, but an increased speed while the slow speed means is still in condition for action, the slow speed driven means being capable of being rendered temporarily inoperative while the high speed means is in action without stopping the continuity of the rotation of the first named shaft.

2. In a machine of the character described, the combination of a reciprocating working part with a counter-shaft, means for driving the counter-shaft constantly in the same direction, means fast on the counter-shaft for transmitting power to said working part to move it at a rapid constant speed in its non-working direction, a second means connected with said countershaft for driving the working part in the opposite cutting direction at a fixed continuous slow speed, a third means connected with the counter-shaft for driving the working table in the cutting direction at a higher contin-

ious speed, the said second means on the countershaft comprising releasing means constituting a part of the driving arrangement and adapted to be automatically released and made idle whenever the third driving means is put into action and while it remains in action, and means constituting a part of said machine for transmitting said motions to the said working part.

10 3. In a machine of the character described, the combination of a reciprocating table for holding the work, a countershaft arranged and adapted to be rotated constantly in one direction, a power shaft parallel to the first shaft mounted on said machine, transmission means connecting said shafts comprising three transmission elements, one constructed and arranged to rotate the second shaft at a high rate of speed 15 in the reverse direction, and two of them being constructed and arranged to rotate the second shaft at two different speeds in the forward or cutting direction and comprising a low speed transmitting means, means for 20 automatically rendering the low speed transmission means inoperative when the higher speed transmission means is in action, and means whereby the three transmission means can be put into and out of action, singly or 25 together, without stopping the constant rotation of the countershaft.

4. In a machine of the character described, the combination of a reciprocatory work table, a countershaft arranged to be 30 rotated constantly in one direction, a table driving shaft mounted on the machine, a gear train connected with the driving shaft to transmit its rotation to the table in the form of reciprocation, a plurality of pulleys 35 fast on the countershaft, a corresponding number of tight and loose pulleys on the driving shaft, the sizes of said several pulleys being so related that two of the pulleys on the countershaft will drive the driving shaft in its forward cutting direction at a 40 low and at a high speed respectively, and that the third pulley on the countershaft will drive the driving shaft in the reverse direction at a high speed, means for connecting 45 the smaller of the first two pulleys on the countershaft positively with the countershaft comprising a ratchet mechanism operated positively by the countershaft which

will operate idly when the driving shaft is driven at a higher speed through the other 55 of the two forward driving pulleys on the countershaft, whereby the rotation of the table driving shaft may be advanced in its forward or cutting direction at a slow speed and then at a higher speed without stopping the rotation of either shaft, and can be reversed without changing the direction of rotation, increasing the velocity, or stopping, the countershaft.

5. In a machine of the character described, the combination of a frame, a reciprocatory table thereon for carrying the work, a countershaft constantly driven in a single direction, a driving shaft on the machine having means for moving the table forward or backward in accordance with the direction of rotation of said driving shaft, two tight pulleys on the countershaft, two pairs of tight and loose pulleys on the driving shaft for receiving rotation from the respective tight pulleys on the countershaft, an open belt on one of said pairs of pulleys, and a cross belt on the other, a third pair of tight and loose pulleys on the driving shaft larger in diameter than said two pairs of tight and loose pulleys, a third wide-faced pulley on the countershaft, a drum keyed to the countershaft inside the third pulley, the third pulley being adapted to turn freely on the countershaft and having a hub having a circumferential series of ratchet teeth, and a ratchet pawl on the drum engaging in said teeth to permit the hub and the third pulley to turn freely in the forward direction at the speed of the counter shaft or faster, whereby, when the belts on the first named countershaft pulleys are connected with the loose driving shaft pulleys, the driving shaft can be driven forward at a slow speed from the third pulley on the countershaft, and whereby, without shifting that belt, the other tight pulley on the countershaft can be connected with its tight pulley on the driving shaft to rotate the driving shaft immediately at a higher speed and rotate the third pulley on the countershaft forwardly at a higher speed without necessitating the shifting of the third belt.

In testimony whereof I have hereunto affixed my signature.

ALBERT M. POWELL.
